UNITED STATES PATENT OFFICE.

ELMER J. WEBER, OF OCONOMOWOC, WISCONSIN.

TWO-CYCLE ENGINE.

1,210,742.

Specification of Letters Patent.

Patented Jan. 2, 1917.

Application filed February 14, 1916. Serial No. 78,092.

To all whom it may concern:

Be it known that I, ELMER J. WEBER, a citizen of the United States, and resident of Oconomowoc, in the county of Waukesha 5 and State of Wisconsin, have invented certain new and useful Improvements in Two-Cycle Engines; and I do hereby declare that the following is a full, clear, and exact description thereof.

10 The present invention relates to new and useful improvements in two cycle internal combustion engines of that type including a cylinder having an inlet port in one end, a work piston and a scavenger piston disposed 15 between the work piston and inlet port and provided with a valve controlled by-pass whereby upon reciprocation of the work piston, fresh gas will be drawn into the cylinder, the scavenger piston being subsequently 20 movable to introduce fresh gas between it and the work piston whereby the gas is compressed for explosion between the pistons upon inward movement of the work piston.

It is in general the object of the present 25 invention to simplify the structure and improve the efficiency of engines of this type, and it is more particularly an object to provide an improved scavenger piston structure with respect to the mounting for the valve 30 of the by-pass.

It is further an object to provide an arrangement wherein the path of movement of the scavenger piston terminates short of the inlet port end of the cylinder, to thus provide 35 a heating chamber for the fresh gases during and adjacent the time of explosion whereby a proper vaporization of the fuel is facilitated.

A further object resides in the provision 40 of an improved means for procuring reciprocation of the scavenger piston.

With the above and other objects and advantages in view, the invention resides more particularly in the novel combination, arrangement and formation of parts more particularly hereinafter described and particularly pointed out in the appended claim.

In the drawings: Figure 1 is a central longitudinal sectional view through a gas 50 engine constructed in accordance with the

present invention and showing the relation of parts assumed in the initial position at the outset of the firing movement. Fig. 2 is a diagrammatic view of the engine similar to the view shown in Fig. 3 and showing the 55 relation of parts assumed at the end of the firing stroke. Fig. 3 is a view similar to Fig. 2 and showing the relation of parts assumed at the end of the scavenging stroke of the scavenger piston. Fig. 4 shows the 60 position at the beginning of the compression stroke.

Referring now more particularly to the accompanying drawings, 5 designates the water cooled cylinder of the engine which is 65 open at its crank end in the usual manner and which has projecting laterally from its other closed end an intake chamber 6 provided in its bottom outwardly of the cylinder with a valve seat 7 with which is associated the inlet valve 8. Slidable in the cylinder is the work piston 9 which is connected to the crank shaft 10 by the usual pitman 11, and an exhaust port 12 is provided in the side of the cylinder at a point immediately 70 inwardly of the inner end of the work piston when the work piston is at its outward limit of movement, a suitable exhaust valve 13 being associated with this port. Slidable also in the engine cylinder between the work 75 piston 9 and the closed end of said cylinder is a scavenger piston 14 and the inner periphery of the cylinder adjacent its closed end is inwardly offset to form an annular seating shoulder 15 for the said scavenger 80 piston at its limit of movement away from the work piston whereby the scavenger piston may firmly seat to form the end of the combustion chamber. It is noted that the work piston at its inner limit of movement 85 is spaced from the scavenger piston in its above mentioned limit of movement whereby the space between these pistons holds the compression charge to be exploded, and to provide for explosion of this charge a chamber 16 is provided in the wall of the cylinder 90 at this point and contains a spark plug member 17.

For procuring a reciprocation of the scavenger piston upon each reciprocation of 100

the work piston, a stem 18 is slidably passed through the closed end of the cylinder and is connected with the scavenger piston by spider arms 19 and this stem outwardly of the cylinder is toothed to provide substantially a gear rack portion which meshes with a segmental gear plate 20 rotatably mounted on a suitable support shaft 21 and this plate is provided with a bowed slot 22 substantially in the form of a semicircle and engaged in this slot is a crank pin 23 carried on a shaft 24 which is driven by the crank shaft 10 of the engine as at 25, the axis of the slot being coincident with the path of movement of the pin 23 whereby the inner side of the slot forms cam surfaces to procure a reciprocative movement of the plate during a respective half rotation of the crank and one end of the inner edge of the slot being flattened at 26 whereby movement of the crank pin thereover will cause a more even movement of the plate and consequently of the scavenger valve stem. To permit a flow of fresh or unused gas into the cylinder past the scavenger piston said piston is provided with a central aperture which is normally closed by a valve 28 and adapted to seat in a depression in the inner face of the scavenger piston, and having its stem slidably mounted in a spider 29 in the said aperture, a spring 30 surrounding said stem and normally urging the valve to closing position.

For simultaneously operating the inlet and exhaust valves, a single cam member 31 is provided on a shaft 32 driven by a chain 33 from the main crank shaft 10 and its cam member 31 carrying a single cam projection 34 which is adapted to engage and depress a valve rod 35 connected with the valves 8 and 13 by levers 36 and 37 respectively, it being noted that the intake valve moves vertically and the exhaust moves horizontally and consequently the first named lever is a straight lever and the second lever is angular in shape although it will be understood that any desired arrangement of levers or valves may be employed, the chief feature emphasized in the present arrangement is that both valves will operate by a single cam member, and this cam member, as is more particularly shown by Figs. 2 and 3 of the drawings operates during the downward movement of the scavenger piston.

Taking up now the operation of the engine structure, it will be seen that in firing position shown more particularly in Fig. 1, the scavenger piston seats on its seat 15 and forms the head of the combustion chamber. Upon firing, the work piston moves outwardly for a quarter rotation of the crank shaft. Upon this quarter revolution being made, the scavenger piston begins to move from its seat coincident with continued

movement of the work piston, which moves to a position wherein its inner end is flush with the outer edge of the exhaust port. In this movement both the inlet and exhaust valves are open and the burnt gases are expelled through the exhaust port at the same time the fresh charge of unused gas is drawn in behind the scavenger piston to fill the cylinder, it being noted that as the scavenger piston projects past the inner edge of the exhaust port at its limit of movement a practically complete expulsion of burned gases is procured. Upon the scavenger piston reaching this limit of movement the valves close and both pistons start their inward movement, as shown in Fig. 3, it being noted that the scavenger piston travels faster than the work piston due to the cam arrangement of the slot 22, and the scavenger piston compresses the unused gas in the cylinder to sufficiently force said gas to overcome the spring holding means of the valve 28 and to pass into the outer portion of the cylinder between the two pistons, the work piston continuing to move inwardly to the initial firing position illustrated in Fig. 1 and to procure a proper compression of the charge of gas between it and the scavenger piston. Thus it is noted that in the combustion chamber proper there is only one valve, this being an inlet valve which naturally tends to remain free of obstructions which might permit leakage through the valve and consequently in the present structure a minimum loss of compression due to leakage is encountered. A still further advantage procured from this arrangement is a reduction of surface upon which carbon is liable to form. Also a considerable quantity of unused gas under slight compression is retained in the end of the cylinder between its closed extremity and the scavenger piston and in the chamber 6 and this quantity of gas receives a considerable heat incident to operation of the engine whereby the proper vaporization of the gas is facilitated.

In the present drawings and in the foregoing description I have described the operations and structure of my invention only in a general manner and it will be understood that in carrying out the invention, various modifications of structure and operation may be found expedient to meet various conditions of services and it is therefore understood that I am to be limited only by the scope of the appended claim, which embodies the spirit of the invention.

I claim:

An internal combustion engine of the class described including a cylinder, a work piston therein, a crank shaft connected with the work piston, a scavenger piston in the cylinder, a stem extending from the scavenger piston outwardly of that end of the

cylinder farthest from the work piston, a pivoted plate in gear mesh with the stem and provided with an arcuate slot, a second shaft connected with the crank shaft, 5 and a crank arm on the second shaft engaged in said slot.

In testimony that I claim the foregoing I

have hereunto set my hand at Oconomowoc, in the county of Waukesha and State of Wisconsin, in the presence of two witnesses. 10

ELMER J. WEBER.
